[57] CLAIM

The ornamental design for an electric trimmer motor housing with an extendable handle, as shown and described.

DESCRIPTION

FIG. 1 is a front elevational view of an electric trimmer motor housing with an extendable handle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a left side elevational view thereof, with the end portion of the handle being shown extended. The broken-line disclosure of the blade in FIGS. 4 and 5 is for illustrative purposes only and forms no part of the claimed design.
